UNITED STATES PATENT OFFICE.

ROBERT G. SANFORD, OF YONKERS, NEW YORK.

ELECTRIC ELEVATOR.

1,103,626.

Specification of Letters Patent. Patented July 14, 1914.

Application filed February 20, 1912. Serial No. 678,819.

To all whom it may concern:

Be it known that I, ROBERT G. SANFORD, a citizen of the United States, residing at Yonkers, in the county of Westchester and State of New York, have invented a new and useful Improvement in Electric Elevators, of which the following is a specification.

My invention relates to controlling systems for electric elevators; and more particularly to that type of electric elevator employing a direct current of electricity for power.

One of the objects of my invention is the provision of a simple, practical and efficient system of electrical control for elevators in which certain parts are made to perform a double function, thereby substantially reducing the number of parts which would otherwise be necessary, and effecting a substantial reduction in the cost of the apparatus as a whole.

Another object of my invention is to provide means for automatically slowing down an elevator car at any desired point in its travel and varying such reduction in speed in accordance with the load.

A further object of my invention is to provide a novel and efficient method of preventing a too sudden reversal of an elevator regardless of the load and inefficiency of the operator, thereby insuring a gradual stoppage of the car without jar or shock, together with a gradual easy start and acceleration, thus preventing any unnecessary strain on the machinery and cables and any disagreeable shock to the passengers.

Another object of my invention is the provision of non-interference features for insuring that the system of control will operate under all conditions as it is intended that it shall operate, regardless of the carelessness of the operator or other factors.

Other objects of the invention will appear hereinafter, the novel combinations of elements being pointed out in the appended claims.

In the accompanying drawings, Figure 1 represents diagrammatically a two speed electric elevator controlling system embodying my invention. The hoisting mechanism itself is not illustrated since the same may be of any desired type or construction and forms no part of the present invention.

Figs. 2, 3, 4, 5 and 6 are fragmentary wiring diagrams showing the motor and cer-

tain other circuits corresponding to the various positions of the controlling switch in the car.

Like reference characters denote similar parts throughout all the figures.

Referring to Fig. 1, C denotes the usual elevator car in which is a controlling switch S, the car being operatively connected to an electric motor M by means of the usual suspension cables. The main line or source of electrical supply is designated by + and -, while 11 is a circuit breaker arranged in both sides of the line and serving to disconnect the source of current supply from the system of control in the event of excessive current flow therethrough. A main line switch is shown at L, while P designates what I term a potential switch and R is the motor reversing switch. The motor M is preferably compound wound having a shunt field winding designated by D and a series field winding designated by F. An accelerating magnet is shown at H and comprises a single magnet operating a series of contacts such as 1, 2, 3, 4, 5 and 6, which control the series field F and the starting, accelerating and stopping resistance G. A stop motion switch is shown at I and comprises a plurality of pairs of switches which are operated at or near the limits of car travel by means of a rod 12 and cams 13, 14, 15 and 16. The mechanism for operating the stop motion switch is not illustrated in detail since the same is well known in the art and is in universal use; it being sufficient to state that the rod 12 and connected cams are rotated in one direction or the other at the limits of car travel by means of a traveling nut on the hoisting drum shaft or in any other well known way. A brake is designated by B and is arranged to apply a friction brake to a pulley on the motor shaft by means of a spring or weight, and is released during the travel of the car by means of an electromagnet. A fast and slow speed switch is shown at E and comprises a magnet which when energized separates a pair of contacts 17 controlling a resistance 18 in series with the shunt field winding of the motor.

I will now go into a more detailed description of the various parts, pointing out the circuits and showing how they act on the different parts to effect the desired results.

The electro-magnet switches L, P and R are similar in construction and each one

comprises a vertically movable or swinging switch arm carrying thereon a plurality of insulated contacts. Corresponding stationary contacts are arranged in alinement with these movable contacts and are adapted to be engaged thereby. Each of these electromagnetic switches is of the solenoid type comprising magnet windings such as 24, 25 and 26, while the switches P and R are also 5 provided with additional solenoids such as 27 and 28 respectively which are preferably of low resistance. It will be noted that the position of the solenoids 27 and 28 with respect to the magnet cores of the corresponding switches P and R is such that when the cores are in their lowermost position as illustrated, any current traversing these solenoids exerts a pull on the cores in a downward direction, whereas, if the cores 10 are in their raised position, a current through the solenoids 27 or 28 will not exert any appreciable downward pull. The reason for this is because when the cores are in their lowermost position they lie 15 within the magnetic field of the solenoids, but when they are in their raised position the cores are removed from this magnetic field and the latter has no effect thereon. For this reason I term the solenoids 27 and 20 28 "hold-down coils" since they tend when energized to hold down their corresponding cores only when the switches are in open or 25 downward position as shown on the drawing.

30 Assuming the circuit breaker 11 in closed position, the operating circuit may be traced from the + main through a fuse 29 and slack cable switch 30 to a safety or emergency switch 31 in the car. This switch 35 being normally in closed position, the circuit continues therethrough to the contacts 32, 32 of the car switch S. Let us further assume that the operator in the car desires 40 to go up and that he moves the switch lever 45 to the left until the contact segment 33 bridges the contacts 32 and 34. The operating circuit now continues through the car switch contacts 32 and 34, and wire 35 to the solenoid 26. From here it returns to the 50 — line by way of the wires 36, 37 and fuse 38. The solenoid 26 being now energized raises its core, thereby closing the contacts 39, 40, 41, 42 and 43 and opening the contacts 44, 45 and 46. This operation established the 55 proper motor connections corresponding to an upwardly moving car but the motor does not as yet start since the main line circuit is still open at the contacts 22 and the contacts 19 and 21 of the main line switch L.

60 The operator next moves the car switch lever still farther to the left until the contact segment 33 bridges the contacts 32, 34 and 47. A circuit is now closed from the + main through the contact 47 and wire 48, 65 stop motion switch contacts 49, wire 50, con-

tacts 42 of the reversing switch R, wire 51, and to and through the parallel connected solenoids 25 and 24 of the potential and main line switches respectively, and by the wire 37 and fuse 38 to the — main. The 70 energization of the solenoids 25 and 24 results in the closing of the switches P and L, thereby establishing a circuit to the motor and brake B.

It will be noted that the circuit to the 75 solenoids 25 and 24 includes the contacts 42 of the reversing switch R, hence the switches P and L will not operate unless and until the reversing switch R has first moved to closed position to make the proper 80 motor armature connections corresponding to an upwardly moving elevator car.

Under the present conditions, the motor circuit may be traced from the + main through the blow-out coil 52, contacts 22, 85 wire 53, contacts 54, wire 55, series field F, starting resistance G, wire 56, hold-down coil 27, contacts 57, wire 58, contacts 41, wire 59, armature brush 60, through the armature A to brush 61, wire 62, contacts 90 40, wire 63, contacts 21 and 19, and through the blow out coil 64 to the — main. The circuit to the brake releasing magnet 68, may be traced from the + line via contacts 22 and 54, contacts 65, wire 66, to and 95 through the brake magnet 68, and by the wire 67 and contacts 20, 21 and 19 to the — main. The shunt field of the motor receives its current through the contacts 22 and 54, wire 55, wire 69, to and through the 100 field D, wire 70, contacts 17, wire 71, wire 63, and contacts 21 and 19 to the — main. The brake being now released, the motor can start to raise the elevator, both field windings being energized. Whereas the 105 motor current energized the hold down coil 27 at this time, the latter has no effect on the switch P since the switch core has already been moved out of the field set up by said coil. The motor will now run at slow 110 speed, since the current flow to its armature and series field winding is limited by the starting resistance G in circuit therewith.

The accelerating magnet H before pointed out has for one of its duties automatically 115 to remove the starting resistance and series field windings from the motor circuit, and its circuit is closed simultaneously with that of the motor by the switches P and L, and may be traced from a point 72 on the starting resistance through the wire 73, contacts 74, wire 75, contacts 23, wire 76, wire 77, winding of accelerating magnet H, wire 78, to the wire 63, and thus to the — line. By following out this circuit it will be observed 120 that the accelerating magnet is in a circuit which is in parallel to the motor armature and a small portion of the starting resistance G, therefore it depends for its operation upon the C. E. M. F. of the motor. As the motor 125 130

starts, its C. E. M. F. gradually increases in value until finally the energization of the accelerating magnet is such that it is enabled to close the contacts 1. This operation short circuits a portion of the starting resistance and permits the motor to increase its speed accompanied by a rise in C. E. M. F. The accelerating magnet is consequently further magnetized and operates to close the contacts 2 which short circuit an additional portion of the starting resistance thereby permitting the motor further to increase its speed. This operation continues, the contacts being closed one after the other in succession, until finally the last contact 6 is operated which short circuits the series field winding F, and the motor now runs at normal slow speed as a shunt machine. The condition of the motor circuits in starting and accelerating to slow speed is clearly seen from an inspection of Fig. 2.

In order to increase the speed of the motor, the operator in the car moves his switch lever to the extreme left, or until the contact segment 33 engages the contacts 32, 34, 47 and 79. This operation establishes a circuit to the fast and slow speed magnet switch E, which may be traced from the + main to the contacts 32 and 79, wire 80, contact 81, wire 82, stop motion switch contacts 83 and 84, wire 85, through the winding of switch E, and by the wires 86 and 87 to the - main. The switch E is at once energized to separate the contact 17 thereby inserting the resistance 18 in series with the shunt field D. The resultant weakening of the field strength of the motor causes the latter to increase its speed, and the elevator car now travels at its normal fast speed.

It will be noted that the circuit to the magnet of switch E includes the contacts 81 of the accelerating magnet, and unless these contacts are closed, it is manifestly impossible to increase the speed of the motor by inserting the resistance 18 in the shunt field unless and until the entire starting resistance as well as the series field has first been short circuited by the accelerating magnet contacts 1, 2, 3, 4, 5, and 6. The advantage of this feature alone is self evident. The motor circuits under the present conditions are clearly seen by referring to Fig. 3.

In order to bring the elevator to rest at any time, the operator moves the car switch lever toward center position until the contact segment 33 runs off of the contact 79. This results in open circuiting the magnet of switch E which latter immediately drops its contacts 17, thereby short circuiting the field resistance 18 and strengthening the motor field which causes the motor to run at a reduced speed, the conditions of the motor circuit being again as shown in Fig. 1. The continued movement of the car switch lever toward center carries the contact segment 33

off of the contact 47, thereby interrupting the circuit of the solenoids 25 and 24, and the switches P and L open their upper contacts. The opening of the switch L disconnects the system from the main line at the contacts 19, 21 and 22, while the opening of the switch P also opens the motor circuit at the contacts 54 and 57 and closes a local or dynamic brake circuit around the motor armature by means of its lower contacts. The opening of these switches also opens the accelerating and brake magnet circuits at a plurality of points. This local or dynamic brake circuit may be traced from the armature brush 60 which is at this time positive and may be considered as +, through the wire 59, contacts 41, wires 58 and 87, lower contacts 88 of switch P, wire 55, series field F and starting resistance G, wire 56, hold down coil 27, lower contacts 89, wire 90, wire 63, contacts 40, wire 62, to the armature brush 61.

It will be observed that since the accelerating magnet is open circuited at this time, the contacts 1, 2, 3, 4, 5 and 6 are open and the series field and resistance G are no longer short circuited thereby. Furthermore, while the resistance G has had its short circuit removed, that portion of it lying between the reference numerals 93 and 94 is again short circuited by the lower contacts 91 of the switch L, through the wires 95 and 96. The motor now runs as a self excited compound generator being driven by the load and the momentum of the parts comprising the elevator machinery, and sends a current through the series field and that portion of the resistance G which is not short circuited by the contacts 91 of the switch L. The result of this dynamic action is to effect a brake or retardation on the motor tending to bring it to rest. The brake B in the meanwhile has been applied and tends further to effect a friction stop of the motor. It will be noted that the brake magnet is normally paralleled by a resistance 97 maintained in circuit by the stop motion contacts 98, 98. The object of this parallel resistance is to retard the action of the brake when it is being applied so that a powerful friction brake may be used which brake will normally release instantly but will be applied gradually and easily. The resistance 97 effects this result in a satisfactory manner, and its principle of operation lies in the fact that an electromagnet will lose its magnetism slowly when the current supply is disconnected, provided a path of relatively high resistance be provided for the brake magnet discharge, which discharge in the case of an elevator magnet brake is considerable.

In order to control the power of the dynamic brake set up by the motor running as a dynamo, the accelerating magnet is

again brought into use. It has been shown that the accelerating magnet circuit was broken at the contacts 23 and 24 when the switches L and P opened and the same immediately operated to remove the short circuit around the series field F and the starting resistance G. As soon, however, as the switch P has made its lower contacts another circuit is supplied to the magnet winding of the accelerating magnet and the same operates its contacts again to short circuit a portion of the resistance G. This circuit may be traced from the motor brush 60, wire 59, contacts 41, contacts 88, wire 55, resistance 99, contacts 100, wire 101, contacts 92, wire 102, wire 77, accelerating magnet H, wire 78, wire 63, contacts 40, and by wire 62 to the armature brush 61. Thus it is seen that the accelerating magnet is connected in series with a resistance 99 across the motor armature. By virtue of its connection the accelerating magnet will operate its contacts to short circuit more or less of the resistance G in the dynamo brake circuit depending upon the E. M. F. of the motor, which in turn is dependent upon its load and speed.

From the foregoing it is seen that I employ the accelerating magnet not only to control the rate of acceleration of the motor in raising or lowering its load, but also to control the stopping of the motor and to vary the reduction of speed in stopping in proportion to the load. This feature I consider of great practical value since heretofore it has been customary to achieve a similar result only by the employment of numerous additional switches and electromagnets together with their accompanying complications and calling for a motor of special design.

In connection with the operation of the accelerating magnet while stopping, it is evident that it would not be desirable to permit the accelerating magnet to short circuit the entire resistance G, since in that case the local or dynamic brake circuit would be of extremely low resistance and the current flow might under certain conditions become excessive particularly when the motor is of large size and power. To guard against this possible contingency, I have provided the contacts 92, which are opened as soon as the movable contacts 4 start to close, and, since the contacts 92 include the circuit of the accelerating magnet when stopping, it is seen that under no conditions can the entire resistance G be short-circuited while bringing the motor to rest. The resistance 99 is for the purpose of reducing the potential applied to the terminals of the accelerating magnet in stopping the motor, since it is obvious that its action would be too rapid were this resistance not used, since the potential of the motor armature at the instant of stopping is comparatively high and the

contacts controlled by the accelerating magnet are arranged to operate when starting the motor at a comparatively low potential so as to short circuit the starting resistance and series field winding in successive steps, thereby effecting a smooth and gradual start and acceleration. 70

It will be observed that the dynamic brake effect in stopping is extremely powerful, much more so than were the motor short-circuited through a resistance with only the shunt field excited. The reason for this may readily be understood when it is considered that the amount of dynamic brake current is not only that due to the armature 75 rotating in a normal field produced by the shunt field winding alone, but this current is sent through the series field winding in the same direction as when starting the motor, hence the actual field strength is considerably in excess of that produced by the shunt field winding alone, and for this reason the C²R loss in the local dynamic brake circuit is substantially increased attended by a powerful retarding or braking action on the 80 motor. In fact I have demonstrated by experiment that a descending elevator car when overloaded fully 50% will be retarded by this dynamic brake action alone to such an amount that the car will barely creep 85 down the hatchway when the mechanical or friction brake is held off entirely, the load driving the motor as a self excited compound generator. This dynamic braking action is effectively and automatically controlled by the motor itself acting through the accelerating magnet and will depend upon the load and speed of the motor. For instance in the case of a lightly loaded descending elevator car as soon as the switches 90

P and L are opened to stop the car and the dynamic brake action becomes effective, the retardation of the motor due to the combined action of the friction brake and the dynamic brake may be sufficient to slow down the 105 motor before the potential of the latter has had time to energize the accelerating magnet an amount sufficient to enable the same to operate any of its contacts. The entire resistance G then, excepting that portion of it short circuited by the lower contacts 91 of the switch L, will be included in the local dynamic brake circuit and the dynamic braking action will be at a minimum corresponding to a lightly loaded car. If the car be 110 heavily loaded and the operator move the controlling switch to stop position, the load tends to keep the motor rotating and the minimum dynamic brake action which we had before in the case of a lightly loaded 115 car does not retard the speed of the motor so readily. In this case the energization of the accelerating magnet will be such that the latter is enabled to close one or more of the contacts 1, 2, etc., thereby lowering the resist- 120

125

130

ance in the local or dynamic brake circuit and permitting more current to flow which of course increases the dynamic brake action on the motor. In this manner the power of the dynamic brake will always depend upon the load conditions which of course is most desirable. At the instant of stopping the retardation of the motor is at first gentle and then increased proportionately to the load and speed. One reason for this is because the friction brake is not instantaneously applied in stopping, since the parallel brake resistance 97 delays the action of the brake. Another reason is because at the instant of stopping, or while the switch is opening its upper contacts and closing its lower contacts, the shunt field circuit is open at these contacts, but is almost immediately closed again across the motor armature at the contacts 88 as soon as the switch P has had time to drop by gravity. The shunt field does not immediately die out when its circuit is opened, since the parallel field resistance 109 opposed this action by permitting the field to discharge therethrough. Thus it is seen that at the time when the dynamic brake circuit is first established the field strength of the motor is rather weak hence the retardation at first is very mild, but rapidly increases as the shunt field builds up and current is sent through the series field windings. This feature is of great practical value since all lost motion in the gears and other parts of the hoisting machine is gently taken up before the brake action has reached its full strength, and in this manner all jars and shocks are avoided and the stopping of the car is effected smoothly and without any unnecessary strain on the cables or other parts.

I am aware that the broad principle of employing a dynamic brake to assist in stopping an elevator or other motor is not new, but the usual method employs either an additional resistance in the dynamic brake circuit or an additional high resistance field winding or both. While the usual method is more or less satisfactory from one standpoint, it involves an additional resistance element which is costly, or else a special motor having an additional field winding for stopping purposes, which not only is costly but otherwise objectionable, since the C^2R loss therein tends to overheat the motor, particularly when the elevator car is frequently started and stopped, and furthermore, the system of control is unnecessarily complicated. Then again when an extra field winding is used on the motor for stopping purposes, it is customary to use this same field winding with a resistance in series with it for effecting a slow running speed. This method is almost certain to overheat the motor and extra field resistance and particularly so when the car is operated for any length of time with the controlling

switch in an intermediate or slow speed position. Not only is there danger of overheating the motor, but there is danger of burning out the extra field and extra field resistance, in which case the extra field would become useless for effecting a dynamic brake stop and the entire duty of retarding and stopping the car would fall upon the friction brake. This method of effecting a slow running speed of the elevator is disadvantageous since the current consumption and heating of the motor are both excessive, and what is more important, if the load tends to overtake the motor a reverse current is sent back through the series field winding and the resultant weakening of the motor field strength may be such as to cause a runaway.

My invention entirely obviates these and other objectionable features since a standard compound wound motor may be used to advantage without any change whatever. Furthermore, there is no trouble from overheating the field windings of the motor due to the dynamic brake current since this current passes through the regular series field winding which of course is of very low resistance, hence the C^2R loss therein is negligible and there is no appreciable tendency to generate heat in the field winding. If the operator in the car desires to run on slow speed for any considerable length of time he may safely do so, since there is no possible danger of overheating the shunt field winding since it is designed to withstand the main line potential for an indefinite period of time; and there can be no possibility of the load overhauling the motor and cause it to generate a reverse current in the series field windings since at this time the motor is running as a plain shunt motor with short-circuited series field. Furthermore this slow speed will be constant, regardless of the load since a shunt wound motor will not vary its speed with varying loads as long as the potential at its brushes remains constant. Another feature of my invention is in using the accelerating magnet and starting resistance both to start and stop the motor and to effect both the start and stop in a manner entirely automatic and depending in every case on load conditions. This feature alone tends toward a substantial economy in cost of manufacture since a very few number of parts are required to do the entire work of controlling the motor and the system of control becomes extremely simple and free from complications and requiring a minimum amount of electrical wiring, and time and labor spent thereon.

Turning once more to Fig. 1, it will be observed that the dynamic brake current in stopping, passes through the hold down coil 27 of the potential switch P. Now, since this switch is in its open or lowermost posi-

tion, the magnetism induced in the core of this switch exerts a powerful downward pull thereon which holds the current carrying contacts 88, 89 and 100, in firm electrical engagement with each other and prevents the switch P from again being closed unless and until the current passing through the hold down coil has dropped to a very low amount, or, what amounts to the same thing, until 10 the speed of the motor has been substantially reduced. The function of this hold down coil is therefore not only to hold the current carrying contacts 88, 89 and 100 into firm electrical engagement with each other, but 15 also to prevent the motor circuit from again being closed to the main line until after the motor has substantially come to rest. This feature alone is of importance since it renders it impossible again to start up or 20 reverse the motor while the dynamic brake current is flowing and the motor being stopped. After the motor has stopped, or at most is rotating very slowly, the current in the hold-down coil will be reduced an 25 amount sufficient to permit the operating solenoid 25 to close the switch again if so desired, but the solenoid 25 has not sufficient power to overcome the action of the hold-down coil 27 while the motor is being 30 stopped, therefore the latter can never be suddenly reversed or started again in the same direction.

It will be observed that in stopping with an ascending elevator car, the switches P and 35 L are in open position, while the reversing switch R remains in closed position. The reversing switch will remain closed whether the circuit to the operating coil 26 be maintained at the contact 34 of the car switch or 40 not. That is to say, that upon breaking the operating circuit of the coil 26 at the contact 34, the coil 26 does not become deenergized since, while the switch R is in closed position, the contacts 39 and 43 establish a self 45 holding circuit for this coil through the resistances 103 and 104, across the motor armature by way of the conductors 62 and 59, respectively. By virtue of this self holding circuit it follows that in stopping, the potential 50 of the motor running as a self excited dynamo will energize the coil 26, to maintain the reversing switch in its raised position until the potential and speed of the motor has dropped a considerable amount or 55 until the motor has substantially come to rest. This feature insures that the dynamic brake action on the motor in stopping cannot be interfered with by the operator in the car or by other influence. The motor must 60 come to rest as it is intended that it shall come to rest, without interference of any kind. As a further precaution it is observed that as long as the switch R remains in closed position the lower contacts 46 thereon 65 are separated, and, since these contacts in-

clude a circuit through the car switch contact 105, it follows that the latter is dead and any reversal of the car switch would have no effect whatsoever on the proper operation of the system. It is immaterial 70 therefore in stopping whether the operator centers his car switch or whether he leaves it in an intermediate position with the contact segment 33 in engagement with the contact 34. 75

The condition of the motor circuit in stopping with an upwardly traveling car is clearly seen in Fig. 4, the load conditions being such that the accelerating magnet has operated one or more of its contacts to short 80 circuit a portion of the starting resistance which at this time is being used as a stopping resistance to absorb the energy of the rotating motor armature and connected hoisting machinery under conditions corresponding to a heavily loaded car. After the motor has come to rest or had its speed reduced substantially to zero, the potential of the armature becomes so low that the current in the self holding circuit of the reversing switch ceases to flow and the latter moves by 85 gravity to open position and all parts are now in their normal position of rest ready for a subsequent operation from the car switch. 90

If it is desired to reverse the direction of rotation of the motor and cause the elevator car to travel downwardly, the car switch lever is moved to the right from its center position until the contact segment 33 comes into electrical engagement with the stationary contact 105, thereupon a circuit will be closed from the main through the wire 106, stop motion contacts 107, wire 108, contacts 46 of the reversing switch, and by the wire 105 51 to and through the windings 25 and 24 in parallel of the respective switches P and L. These switches will operate to close their upper contacts and open their lower contacts, thereby establishing a circuit from the main 110 line to the motor armature, motor fields, brake magnet and accelerating magnet as before in the case of an upwardly moving elevator car, except in the present case the armature connections are reversed at the 115 lower contacts 44 and 45 of the reversing switch, and the motor will in consequence rotate in a reverse direction. As before, the accelerating magnet will automatically control the short circuiting of the starting resistance and series field winding in graduated steps, so as to effect a smooth acceleration of the motor to normal slow speed running conditions, while a further movement of the car switch lever onto contact 109 establishes a circuit to the fast and slow speed magnet E, which will insert the resistance 18 into the shunt field circuit, thereby permitting the motor to attain full speed. The 120 conditions of the motor circuits when run- 125 130

ning at normal slow speed with the starting resistance and series field winding short circuited are shown in Fig. 5, which corresponds very nearly to the conditions of the 5 motor circuits shown in Fig. 2, where the motor is running at slow speed in the opposite direction, only in the present case the line current passes through the motor armature in a reverse direction and the motor 10 circuit also includes the hold-down coil 28 of the reversing switch R. This hold-down coil tends to hold the lower contacts of the reversing switch in firm electrical engagement with each other and prevents the operating coil 26 from raising the reversing switch should for any reason be accidentally energized as might occur in case of an accidental short circuit or ground on the 15 system.

20 In stopping with a descending elevator car it will be observed that all three switches L, P and R are opened at their upper contacts, and that the dynamic brake circuit includes both of the hold down coils 27 and 25 28, so that, as long as the motor is generating any appreciable amount of current it will be impossible to close either the switches R or P, hence there can be no possibility of again starting the motor or causing it to 30 reverse unless and until it has substantially come to rest. The condition of the motor circuits when stopping with a descending elevator car is clearly shown in Fig. 6 which corresponds very nearly with that shown in Fig. 35 4, only in the present case the armature connections are reversed and both of the hold down coils 28 and 27 are in series with the dynamic brake circuit. It will be observed that in stopping an ascending elevator car, 40 as soon as the same substantially comes to rest, the reversing switch automatically moves to its downward position with the contacts 44 and 45 in electrical engagement respectively. Thus, if the car be heavily 45 loaded and the friction brake is unable to hold the load, the latter will tend to drive the motor backward with rapidly increasing acceleration. But since the reversing switch R has at this time closed its lower contacts 50 44 and 45, the dynamic brake circuit is closed and so the motor will act as its own brake, as before pointed out, so that the car cannot attain any appreciable speed in a downward direction no matter what the load 55 may be. This feature is in itself of great practical value since it entirely obviates the possibility of a runaway car due to a defective mechanical or friction brake.

60 The safety or emergency switch 31 in the car may be operated at any time to stop the motor by opening the operating circuit; while the slack cable switch 30, which is arranged in the usual manner to operate and open its contacts upon any slack occurring 65 in the cables, effects the same result.

I sometimes parallel the shunt field winding by a high resistance element 109 which is often useful in regulating the speed of the motor to any desired amount within practical limits, and also serves as a safeguard to 70 the shunt field winding in case the circuit of the latter should for some reason become suddenly interrupted, the resulting field discharge being dissipated and kept from attaining too high a potential by this parallel 75 resistance.

I will now point out the operation of the stop motion switch I, it being understood from what has been said before that this switch operates only at the limits of car 80 travel in both directions.

Assuming the car to be descending at full speed, and the car switch lever be maintained in its extreme right hand position. As the car approaches its lower limit of 85 travel, the rod 12 and connected cams 13, 14, 15 and 16 will rotate in a right hand or clockwise direction. Owing to the shape of these cams, the switch contact 83 will open first, thereby interrupting the circuit to the 90 fast and slow speed magnet switch E, and causing the latter to short circuit the resistance 18, thereby strengthening the shunt field and slowing down the motor. Immediately after this has taken place, a further 95 rotation of the shaft 12 effects the opening of the contacts 107 which interrupts the circuit of the operating solenoids 25 and 24 of the switches P and L, respectively, thereby permitting these switches to open and thus 100 disconnect the motor from the main line, and putting into operation the dynamic brake and friction brake B. Simultaneously with the opening of the contacts 107, or immediately afterward, the cam 15 opens the 105 contacts 98, which open circuits the parallel brake resistance 97 and permits the brake B to be applied instantly with full power. At this time the motor will in all probability be completely stopped, but, if for some unaccountable reason the switches and other parts should be disabled and fail to perform their normal functions, a further movement of the car in a downward direction will cause the cam 16 simultaneously to close the 110 contacts 110 and 111. The closing of the contacts 110 practically short circuits the main line through the main fuses 10 and circuit breaker 11, the effect of which will either blow the main fuses or open the circuit breaker or both, and in any event all current supply is absolutely cut off from the 115 controlling system.

While I desire to insure the opening of the circuit breaker or the blowing of the 125 main fuses in case the contacts 110 are closed by the stop motion switch, I do not favor placing a dead short circuit across the line, but prefer to have this short circuit contain at most a very low resistance, 130

and I do this by connecting one of the contacts 110 through the wire 63 and contacts 21 and 19 to the — main, while the other contact 110 is connected to the starting resistance G at a point 93, one end of the series field being connected through the switch contacts 54 and 22 to the + main. Thus it is seen that the closure of the contacts 110 short circuits the line through the series field and a very small portion of the starting resistance, the ohmic resistance of this short circuit being low enough to permit a sufficient current to flow through the main fuses and circuit breaker to effect the desired result. The closing of the stop motion contacts 111 simultaneously with the contact 110 establishes an extremely powerful dynamic brake action, since the dynamic brake circuit at this time includes the series field and that small portion of the starting and stopping resistance G lying between the point 93 thereon and the series field. This circuit may be traced from the + side of the motor at the brush 61, to the wire 62, through the contacts 44 of the reversing switch R, contacts 111, series field F, a small portion of the resistance G to the point 93, through the contacts 110, wire 63, hold down coil 28, contacts 45, wire 59 to the — side of the motor at the brush 60.

It will be observed that owing to the low ohmic resistance of the dynamic brake circuit under these conditions, the current generated by the motor acting as a dynamo will be of large amount thereby effecting a maximum dynamic braking action which will rapidly bring the car to a very slow speed so that even though the friction brake should fail to operate to stop the car the latter will proceed to the end of its run when it will gently bottom without shock or jar since it is moving at a very slow speed. This feature of simultaneously opening the main line circuit and establishing a dynamic brake action of great power I consider of great practical value in elevator practice. Heretofore, the stopping of the car has been dependent upon the operation of one or more of the electrically operated switches, and should any one of these switches fail to operate at the proper time, which is sometimes the case, the stopping action at the limits of car travel fails to take place and the car will in all probability be wrecked and the passengers injured or killed.

With an elevator system arranged according to my invention it is immaterial whether the motor controlling switches stick in closed position or otherwise fail to operate at the proper time, since the closing of the stop motion contacts 110 and 111 by the cam 16 is absolutely positive and does not rely upon springs or gravity. Furthermore the closing of these contacts insures that the system will immediately be disconnected from

the main line at the circuit breaker 11 or main fuses 10 or both, and that the motor armature will be short circuited through its series field winding and a low resistance element resulting in a powerful and effective 70 brake action.

My invention absolutely prevents the car from getting beyond control even though the car be descending with a heavy load and the friction brake fail to operate at the 75 lower limit of travel. The braking action of the motor acting as a dynamo is of such power at this time that the speed of the car is rapidly reduced, and while this dynamic brake action will not bring the car to a 80 dead stop, it will reduce its speed to such an amount that the car will barely creep along and when the bottom of the hatchway is reached the car will be stopped without 85 injury to itself and without injury or discomfort to the passengers.

The operation of the stop motion switch when the car is ascending is similar to that just described, excepting that in this case the shaft or rod 12 will be rotated in a left 90 handed or counterclockwise direction, thereby effecting the successive operation of the switch contacts 84, 49, 98, 110 and 111.

The disclosure of my invention herein made is that of the preferred embodiment 95 thereof, and I desire not to be limited to the precise construction of details set forth in said disclosure, as the same may be varied in many particulars without departing from the spirit and scope of my invention.

What I claim, and desire to secure by Letters Patent of the United States is:

1. In an electric elevator, the combination of a car, a motor operatively connected to said car, a source of electrical supply, a 105 normally closed reversing switch arranged to reverse the motor connections so as to cause the motor to run in either direction, a potential switch adapted when in one position to close a circuit from the source of 110 electrical supply to the motor, and when in another position to close a local or dynamic brake circuit on the motor, and means for holding said reversing switch against movement in either direction for both positions 115 of said potential switch during the time the motor is in motion.

2. In an electric elevator, the combination of a motor, a resistance, means for connecting said resistance in series with said motor 120 across the line in starting in both directions and for connecting said resistance in parallel with said motor in stopping, and means for controlling said resistance both in starting and stopping.

3. In an electric elevator, the combination of a motor, a resistance, means for connecting said resistance in series with said motor across the line in starting in both directions and for connecting said resistance in paral- 130

1. In an electric elevator, the combination of a motor, a resistance, means for connecting said resistance in series with said motor across the line in starting in both directions and for connecting said resistance in parallel with said motor in stopping, and means controlled by the motor for varying said resistance both in starting and stopping. 70

2. In an electric elevator, the combination of a motor, a resistance, means for connecting said resistance in series with said motor across the line in starting in both directions and for connecting said resistance in parallel with said motor in stopping, and means controlled by the motor for varying said resistance both in starting and stopping. 75

3. In an electric elevator, the combination of a motor, a resistance, means for connecting said resistance in series with said motor across the line in starting in both directions and for connecting said resistance in parallel with said motor in stopping, and means automatically controlled for varying said resistance both in starting and stopping. 80

4. In an electric elevator, the combination of a motor, a resistance, means for connecting said resistance in series with said motor across the line in starting in both directions and for connecting said resistance in parallel with said motor in stopping, and means controlled by the motor for varying said resistance both in starting and stopping. 85

5. In an electric elevator, the combination of a motor, a resistance, means for connecting said resistance in series with said motor across the line in starting in both directions and for connecting said resistance in parallel with said motor in stopping, and means controlled by the motor for varying said resistance both in starting and stopping. 90

6. In an electric elevator, the combination of a motor, a resistance, means for connecting said resistance in series with said motor across the line in starting in both directions and for connecting said resistance in parallel with said motor in stopping, and means controlled by the varying potential of the motor armature for short-circuiting said resistance both in starting and stopping. 95

7. In an electric elevator, the combination of a main line circuit, a compound wound motor, a resistance, an electro-responsive device adapted when in one position to connect the series field winding, motor armature and said resistance in series across the main line, and when in another position to connect the motor armature, series field winding and said resistance in a local or dynamic brake circuit, and means controlled by the motor both in starting and stopping for varying said resistance for both positions of said electro-responsive device. 100

8. In an electric elevator, the combination of a compound wound motor, of a main line circuit, a resistance means for connecting said motor, series field and resistance in a series circuit across the line, means for short circuiting said series field and resistance in starting the motor, means for connecting said series field and resistance in series with each other and in parallel to the motor armature in stopping, and means controlled by the motor for short circuiting a portion only of said resistance in stopping. 105

9. In an electric elevator, the combination of a motor, a resistance arranged to be connected in circuit with the motor both in starting and stopping in both directions, and means controlled by the motor in accordance with the load for varying said resistance both in starting and stopping. 110

10. In an electric elevator, the combination of a motor, a resistance arranged to be connected in circuit with the motor both in starting and stopping in both directions, and means controlled by the motor for varying said resistance both in starting and stopping. 115

11. In an electric elevator, the combination of a motor, a single resistance used both for starting and stopping the motor in both directions of rotation, and means controlled by the motor in starting and stopping for varying said resistance. 120

12. In an electric elevator, the combination of a motor, a resistance used both for starting and stopping said motor in both directions of rotation, and an electro-responsive device controlled by the motor arranged gradually to short circuit said resistance both in starting and stopping. 125

13. In an electric elevator, the combination of a motor, a resistance used both for starting and retarding the motor, means controlled by the motor for short circuiting said resistance both in starting and stopping, and means for preventing all of said resistance from being short-circuited during the retardation of the motor. 130

14. In an electric elevator, the combination of a compound wound motor, of a resistance, electro-magnetic switch apparatus arranged to connect said resistance in series with the motor in starting and for connecting said resistance in parallel with a circuit comprising the motor armature and series field winding in stopping, and means for varying said resistance both in starting and stopping. 135

15. In an electric elevator, the combination of a compound wound motor, of a resistance, electro-magnetic switch apparatus arranged to connect said resistance in series with the motor in starting and for connecting said resistance in parallel with a circuit comprising the motor armature and series field winding in stopping, and means controlled by the motor for varying said resistance both in starting and stopping. 140

16. In an electric elevator, the combination of a compound wound motor, a resistance, a main line circuit, switch mechanism arranged to connect said motor and resistance in series across the main line in starting, and for connecting the motor, series field winding and resistance in a local or dynamic brake circuit in stopping, and means operated by the motor for varying said resistance both in starting and stopping. 145

17. In an electric elevator, the combination of a motor, of a resistance used both for starting and stopping said motor, an electro-responsive device arranged automatically to control said resistance, an additional resistance, and means for inserting said additional resistance in series with the magnet of said electro-responsive device during the operation of stopping the motor. 150

18. In an electric elevator, the combination of a motor, of a resistance used both for starting and stopping said motor, an electro-responsive device arranged automatically to control said resistance, an additional resistance, and means for inserting said additional resistance in series with the magnet of said electro-responsive device during the operation of stopping the motor. 155

tion of a car, a motor operatively connected thereto, a brake for said motor, means for effecting a gradual application of said brake to stop the car within its normal limits of travel, and means for effecting a quick application of said brake when the car exceeds its normal travel in either direction.

19. In an electric elevator, the combination of a car, a motor operatively connected thereto, a brake for said motor, means for effecting a gradual application of said brake to stop the car within its normal limits of travel, and automatic means controlled by the motor for effecting a quick application of said brake when the car exceeds its normal travel in either direction.

20. In an electric elevator, the combination of a car, a motor operatively connected thereto, a main line circuit, a circuit-interrupting device connected in said main line circuit, and means for causing an abnormal flow of current through said circuit interrupting device to effect the operation of the latter when the car exceeds its normal limits of travel.

21. In an electric elevator, the combination of a car, a motor operatively connected thereto, a main line circuit, a switch adapted when in one position to close a circuit to said motor from the main line, and when in another position to close a local or dynamic brake circuit around the motor, and means for causing an abnormal flow of current to effect the opening of said switch to close the

local or dynamic brake circuit when the car exceeds its normal limit of travel.

22. In an electric elevator, the combination of a car, a motor operatively connected thereto, a main line circuit, a switch adapted when in one position to close a circuit to said motor from the main line, and when in another position to close a local or dynamic brake circuit around the motor, and means controlled by the car for causing an abnormal flow of current to effect the opening of said switch to close the local or dynamic brake circuit when the car exceeds its normal limit of travel.

23. In an electric elevator, the combination of a car, a motor operatively connected thereto, a reversing switch for the motor, electromagnetic means for moving said switch in one position and for permitting gravity to move it in another position, a dynamic brake circuit for said motor which is established whenever said reversing switch is in its gravity operated position, and means for maintaining said switch against movement in either direction while the said motor is in motion.

In testimony whereof, I have signed my name to this specification in the presence of two subscribing witnesses.

ROBERT G. SANFORD.
